(57) **ABSTRACT**

This invention is embodied in a bracket for installing side-mount, slide-out shelving. The key to this invention is an offset section of the bracket that permits the bracket to engage with a tab 4 on the side-mount slide. By engaging the bracket and the side-mount slide without having to use a fastener, an installer can locate and fasten the bracket to the existing cabinet base, thus securing the side-mount slide to the cabinet.

BRACKET FOR INSTALLING SIDE-MOUNT,
SLIDE-OUT SHELVING

FIELD OF THE INVENTION

The present invention relates to cabinet organizers and in particular to full extension side-mount slides in the installation and use of slide-out shelving solutions for cabinets.

BACKGROUND

Slide-out shelving is a great way to organize cabinets. Many different solutions exist to create a cabinet with slide-out shelving or to retro-fit an existing cabinet with slide-out shelving. A side-mount drawer slide (or “side-mount slide”) is a common way to install slide-out shelving. A common example of a side-mount slide **2** is shown in FIGS. 1 and 2.

It can be difficult to install side-mounted slides accurately, especially when retro-fitting side-mount slides to an existing cabinet. Typically, an installer must at least partially crawl into the cabinet in order to measure, align, level, and mount the hardware. Often times it can be difficult to line everything up correctly so that the slide out shelving ends up in the right place. Part of the difficulty arises when measuring, drilling and mounting hardware horizontally because the existing space is limited and the restricted viewing angles are challenging. Typical side-mount slides **2** require an installer to drive fasteners horizontally through holes **28** in tabs **4** to secure the side-mount slide to a cabinet. See, e.g., FIGS. 1 and 2.

What is needed is a side-mounting slide system that simplifies installation so that slide-out shelving can be installed into the bottom of a cabinet quicker, easier and more accurately.

SUMMARY OF INVENTION

The subject of this invention is embodied in a bracket **10** that allows a user to install a side-mount slide **2** onto the bottom of a cabinet. The key to this invention is an offset section of the bracket that permits the bracket **10** to engage with tab **4** on the side-mount slide **2**. By engaging the bracket **10** with tab **4** of the side-mount slide, an installer can locate and fasten the side-mount slide to a horizontal surface instead of a vertical surface, which makes securing the side-mount slide to the existing cabinet base easier and more accurate.

The preferred bracket **10** is L-shaped, having a first leg **12** and a second leg **14**. The first leg **12** has a first section **16** connected to a second section **18** and the second section **18** connected to a third section **20**. The first section **16** and third section **20** are oriented in a first plane **22** and the second section **18** is oriented in a second plane **24** offset from the first plane **22**.

BRIEF DESCRIPTION OF DRAWINGS

FIG. 1 illustrates a prior art side-mount slide **2** with extension rails retracted.

FIG. 2 illustrates a prior art side-mount slide **2** with extension rails extended.

FIG. 3 illustrates a perspective view of an embodiment of the invention.

FIG. 4 illustrates a perspective view of an embodiment of the invention.

2

FIG. 5 illustrates a side view of an embodiment of the invention.

FIG. 6 illustrates a back view of an embodiment of the invention.

FIG. 7 illustrates a front side view of a side-mount slide **2** with bracket **10** engaging with tab **4**.

FIG. 8 illustrates a perspective end view of a side-mount slide **2** with bracket **10** engaging with tab **4**.

FIG. 9 illustrates a perspective back side view of a side-mount slide **2** with bracket **10** engaging with tab **4**.

FIG. 10 illustrates a bracket **10** having nubs **26** configured to engage with holes **28** on tab **4** when the bracket **10** is engaged with the tab **4**.

FIG. 11 illustrates a front side view of a side-mount slide **2** with bracket **10** engaging with tab **4** and nubs **26** engaging with holes **28** on tab **4**.

OVERVIEW OF THE PREFERRED
EMBODIMENT

The preferred embodiment of the bracket is shown in FIGS. 3-6. The preferred bracket **10** is L-shaped and constructed from metal, having a first leg **12** and a second leg **14**. The first leg **12** has a first section **16** connected to a second section **18**. The second section **18** is connected to a third section **20**. The first section **16** and third section **20** are oriented in a first plane **22** and the second section **18** oriented in a second plane **24** offset from the first plane **22**. For use with typical side-mount rails, the first leg **12** would be about one and seven-eighth inches long and the second leg **14** be one and a quarter inches long.

The purpose of offsetting the second section **18** is so that the second section **18** can engage with tab **4** on a side-mounted slide **2** as shown in FIGS. 7-9. In operation, this can be accomplished by sliding the second section **18** behind tab **4** while keeping the first section **16** and the third section **20** in front of the tab **4**. In this way, no fasteners are needed to connect the bracket **10** with the tab **4**. For use with typical side-mount rails, the second section **18** would preferably be offset one-eighth of an inch from the first and third sections (**16, 20**) but an offset between one sixteenth and one quarter would be satisfactory. Of course, the most important factor is that the offset amount is at least as much as the thickness of the tab **4**.

Once engaged, a user can use a fastener of choice to fasten the bracket **10** to a surface through the perforations **30** on the second leg **14**. The fastened surface is preferred to be a top surface of the bottom of the interior of a cabinet or a bottom surface of the top of the cabinet. But, the user can use perforations **30** to fasten the bracket (and engaged side-mount slide) to any surface desired. By engaging bracket **10** with a side-mount slide, a user can fasten the side-mount slide perpendicularly to the face of the slide.

Optionally, the bracket **10** can have one or more raised nubs **26**. The purpose of a raised nub **26** is to engage a hole **28** in the tab **4**. While it has been found putting nubs **26** on the bracket **10** is not necessary to achieve satisfactory connection, adding nubs **26** can assist in further strengthening the engaged connection between the bracket **10** and the tab **4**. For the purposes of this specification, a “nub” is a raised element oriented on the bracket to engage with hole **28** on tab **4**. A nub can take a variety of shapes. It is preferred that the nub take a dome shape for its centering ability, but most any shape will suffice as long as it is configured to fit snugly within hole **28**.

It is preferred to add perforations **30** to the second leg **14** of the bracket **10**. The purpose of the perforations **30** is to

accept a fastener for securing the second leg **14** to the cabinet. It is preferred to use a fastener through perforations **30** to secure the second leg to a horizontal surface. For example, the horizontal surface could be the top of the bottom surface of the interior of the cabinet (the floor) or the bottom side of the top of the interior of the cabinet (the ceiling). The perforations **30** can take many shapes, but it is preferred to have at least one perforation **30** be relatively elongated to allow for some adjustability during installation.

The transition between (a) the first section **16** and the second section **18** and (b) the second section **18** and the third section **20** preferably matches the size and shape of tab **4**. In other words, the contours of the offset section of the first leg **14** should be configured to mate with the shape of tab **4**.

In operation, the preferred method for installing side mounted slide-out shelving is as follows:

1. engaging a first leg of an L-shaped bracket to a tab of a side-mounted slide by sliding a second section **18** of the first leg **12** behind tab **4** while keeping the first and third sections (**16, 20**) of the first leg **12** in front of tab **4**,
2. orienting the side-mounted slide in a cabinet, and
3. fastening the second leg **14** of the L-shaped bracket **10** to the cabinet via perforations **30**.
4. Connecting a shelf to the side-mounted slide.

While various embodiments have been described above, it should be understood that they have been presented by way of example only, and not limitation. Thus, the breadth and scope of a preferred embodiment should not be limited by any of the above-described exemplary embodiments, but should be defined only in accordance with the following claims and their equivalents.

The invention claimed is:

1. A method for connecting a side-mount slide to a bracket comprising the steps of:

selecting a side-mount slide comprising a tab, the tab oriented co-planar to a face of the side-mount slide, selecting an L-shaped bracket comprising a first leg and a second leg, the first leg comprising a first section connected to a second section and the second section connected to a third section, the first section and the third section are not adjacent to each other because the second section is positioned between the first section and the third section, the first and third sections ori-
